UNITED STATES PATENT OFFICE.

LEWIS B. DOMAN, OF SYRACUSE, NEW YORK, ASSIGNOR TO THE AMPHION PIANO
PLAYER COMPANY, OF SYRACUSE, NEW YORK, A CORPORATION OF NEW YORK.

VALVE FOR PNEUMATIC ACTIONS.

1,017,857.

Specification of Letters Patent.

Patented Feb. 20, 1912.

Application filed March 25, 1910. Serial No. 551,545.

To all whom it may concern.

Be it known that I, LEWIS B. DOMAN, a citizen of the United States, and a resident of the city of Syracuse, county of Onondaga, and State of New York, have invented certain new and useful Improvements in Valves for Pneumatic Actions, of which the following is a specification, reference being had to the accompanying drawings, in

10 which—

Figure 1 is a sectional view of my improved valve; Fig. 2 is a top plan view looking downwardly on Fig. 1; Fig. 3 is a plan view of the bottom looking upwardly at Fig. 1, with the lower part of the air chamber removed; Fig. 4 is an enlarged view of a part of said valve shown in Fig. 1.

Similar letters refer to similar parts throughout the several figures.

20 This invention relates to valve mechanisms in pneumatic actions, more particularly used in mechanical musical instruments, and its object, among other things, is to provide a simple and efficient means for controlling 25 the air passages leading from the pneumatic action proper to the wind chest, so that the operation of the instrument, as for instance an automatic piano player, can be cut out of use during the re-winding of the 30 music from the take-up roll to the music roll. My improved device, however, is not limited to musical instruments, but may be used in any other mechanism where it is desirable to control the air passage.

35 Referring now to the figures, and assuming that the pneumatic action is one employing rarefied air, or that operates under a partial vacuum, X represents an air chamber for the elements making up the valve.

40 A is a pipe connected to the pneumatic action.

B is a pipe or passage connected to the wind chest of the bellows.

D is a flexible diaphragm, preferably 45 made of leather, extending horizontally across the air chamber X and located to close the orifice of the passage A at C, as shown in Fig. 1.

E is a tube with a manually controlled 50 valve placed in any position convenient to the operator; F is another tube connected below the diaphragm D as shown in Fig. 1, and likewise with a nipple G containing a restricted passage or air vent.

55 The operation of my improved valve is as

follows. The passage B is under partial vacuum or rarefied air and is connected with the pipe or passage A as shown in Fig. 1. If air at atmospheric pressure be admitted to the compartment M below the diaphragm 60 through the tube E, such diaphragm D will at once rise and close the passage at the lower end of the pipe A at C, thus preventing air under a partial vacuum from passing through the passage A and thereby cutting out of operation the pneumatic action or other device operating under the partial vacuum which may be connected to the pipe A. When it is desired to open the passages 65 so as to connect A with B the tube E is 70 closed and the excess pressure, that is the pressure of the atmosphere in the compartment M under the diaphragm D is immediately equalized through the passages F and G, and this will cause the diaphragm E to 75 fall and restore the unrestricted passage through the pipe A, the compartment N, and the pipe B.

What I claim as new and desire to secure by Letters Patent is the following, viz:— 80

1. In combination with a pneumatic action, a valve comprising an air chamber, a conduit leading from the wind chest into said air chamber, a second conduit leading from the pneumatic action and projecting within said air chamber to form a valve-seat, a flexible diaphragm extending across said air chamber to provide a closure for said valve-seat, means for admitting air to inflate said diaphragm to close the valve, 90 and means to equalize the air pressure on both sides of the diaphragm to open the valve.

2. In combination with a pneumatic action, a valve comprising an air chamber, a conduit leading from the wind chest into said air chamber, a second conduit leading from the pneumatic action and projecting within said air chamber to form a valve-seat, a flexible diaphragm extending across said air chamber to provide a closure for said valve-seat, a tube opening to atmospheric air below said diaphragm to inflate same to close the valve, and a restricted passage connecting the compartments on opposite sides of the diaphragm to deflate same to open the valve when the tube controlling atmospheric air is closed.

3. In combination with a pneumatic action, a valve comprising an air chamber X, 110

the pipe A and the pipe B, both opening into the exhaust chamber N of the air chamber X, the pipe B projecting into said air chamber to form a valve-seat C, the diaphragm D extending across said air chamber and adapted to close the valve-seat C, the tube E to admit air at atmospheric pressure below the diaphragm D to inflate same to close the valve-seat C, and the restricted

air passages F, G, connecting the compartments M and N on opposite sides of the diaphragm D to deflate same to open the valve when the tube E is closed. 10
